UNITED STATES PATENT OFFICE.

CARL MORADELLI, OF MUNICH, GERMANY.

CAR-COUPING.

SPECIFICATION forming part of Letters Patent No. 558,409, dated April 14, 1896.

Application filed October 26, 1894. Serial No. 527,078. (No model.)

To all whom it may concern:

Be it known that I, CARL MORADELLI, locksmith, a subject of the King of Bavaria, and a resident of Munich, in the Kingdom of Bavaria, German Empire, have invented a certain new and useful Improved Railway-Car Coupling, of which the following is a full, clear, and exact description.

The present invention relates to that class of car-couplings for railway-cars which are operated from the side of the rails and thus obviate the necessity of the attendants getting between the cars in order to couple the same.

15 The device consists mainly of swinging hooks attached to the car ends above stationary spring-retained links or loops, said hooks being retained above said links or loops previous to coupling the cars by means of eccentrically rigidly attached to a horizontal bar, adapted to be operated from the side of the car, and which when turned down allows the hook to fall into the link or loop of the next car, which has been brought into position under the same, the hook of the second car falling into position into the loop or link of the first car. The openings or orifices of the two loops or links are, on the cars approaching each other, brought into position one over the other, so that each of the hooks hitches into or through both the loops, and is secured therein by suitable mechanism, as hereinafter more particularly described.

According to a modification of my invention the loops may be arranged in a vertical instead of a horizontal plane and the hooks be made to swing in a horizontal instead of a vertical plane.

In order to make the present specification more easily intelligible, reference is had to the accompanying drawings, in which similar letters denote similar parts throughout the several views.

Figure 1 is a side elevation of the coupling; Fig. 2, a sectional side elevation; Fig. 3, a half-plan; Fig. 4, a side elevation of a modified form of my invention; Fig. 5, a plan of Fig. 4; Fig. 5^a, a plan of a further modification showing the links or loops having tapering extremities; Fig. 6, a sectional elevation showing links with tapering extremities and vertically-swinging hooks, and Fig. 7 a similar elevation showing the hooks in position in the links or loops.

50 To the end beam A of the carriage-frame 55 is pivoted a hook g at g², said hook being adapted to swing in a vertical plane, and being held in its upper position when out of engagement by means of an eccentric B, keyed to a spindle h, revolubly mounted on the 60 buffers, and having at its ends lever-arms carrying weights H, Figs. 1 to 3. At the opposite side to the throw of the eccentric the same carries a hook i, adapted when the said eccentric is thrown over to engage over a 65 shoulder of the said hook g, as shown at Fig. 3. Beneath the said hook g and passing through the frame A of the carriage is a bar a, having formed at its extremity a frame or loop a', said bar carrying at its rear extremity a sleeve 70 b, having a coarse exterior screw-thread. Behind the said sleeve is arranged around the bar a a spiral spring c, bearing with its forward end against the end of the sleeve b or against an intermediate disk and with its rearward 75 end against a nut arranged on the bar a. An exterior sleeve d engages the exterior thread of the said sleeve b, said exterior sleeve being secured against longitudinal movement on the thread of the said sleeve b by means of a 80 suitable strap d', attached to the carriage-frame, but being free to revolve. This exterior sleeve carries a worm-wheel d², into which meshes a worm f, mounted on a horizontal spindle D', suitably supported in the 85 carriage-frame and having at its end a hand-wheel D.

85 The frame or loop of the bar a at a' is of sufficient dimensions and placed in such position under the hook g that when this hook 90 and the hook of the carriage to be coupled onto the said carriage fall down to connect up the cars both the said hooks g shall pass through the said loop or frame a.

The loops or frames a' of the several cars 95 are so arranged that when the cars are run together to be coupled the two adjacent frames lie one over the other, as shown at

Fig. 2, sufficient play being left in the relative positions of the two loops to allow for the difference in the height of the cars, caused by the possible variation in the loading of the said cars, whereby one would be lower than the other. A play of about three to four inches will be sufficient, so that no matter to what extent either one or other of the cars may be loaded with regard to the other the loops will always have room to pass each other and overlap.

The operation of the device is as follows: When the carriages are run together to be coupled, the hooks *g* are both in the position shown at the right-hand side of Fig. 2, the loops or frames *a'* overlapping each other. On turning round the spindle *h* the eccentric *B* will be thrown over and let down the hooks *g g*, which pass through the loops *a'*. Simultaneously, however, the hooks *i* at the opposite side of the eccentrics will be thrown over the shoulders of the hook-shanks *g* and retain the same in position. By turning the hand-wheel *D* the bars of the frames *a'* will be tightened up against the hooks by means of the worm *f*, worm-wheel *d*, and sleeves *d²* and *b*.

In the modification shown in Figs. 4 and 5 the hooks *g' g'* are made to swing in a horizontal plane, while the frames *a² a²* are turned round a quarter of a turn. The hooks *g' g'* are operated by means of the rods *M*, adapted to slide in guides on the buffers and having downwardly-extending pins *M'*, which engage in slots *G²* of the said hooks, said rods *M* being retained in either position by means of transverse pins *o o*, inserted through the rods at either side of the strap which guides the said rod. The operation of this part of the invention will be intelligible from the foregoing specification and needs no further explanation.

In the modification shown in Figs. 6 and 7 the frames *a³ a³* are made with tapering extremities running out to a point, and the said frames are not rigidly supported in the horizontal plane, as heretofore described, but are allowed a certain amount of play by the following arrangement: The sleeve *b* fits loosely over the bar *a* and has its rearward end provided with a rounded-off surface, against which a disk *n* on the said bar rests, the contacting surface of the said disk being also spherically formed. Behind the disk is a spring *c* of greater strength than the buffer-springs, said spring resting at its opposite extremity against a nut on the bar *a*. At the opposite side of this nut is a second and lighter spring *c'*, bearing with its spherically-formed disk against a stationary bearing *l*, arranged on the car-frame and through which the rod *a* passes, being free to slide in the orifice. A spring *b'* is placed in the sleeve *b* between it and the rod *a*, which tends to hold the said rod *a* in its lowest position on the interior of the said sleeve *b*.

The rotation of the sleeve *d²* and worm *d* is

facilitated by ball-bearings, of which the balls are arranged in grooves at the ends of the said sleeve *d²* and in corresponding recesses in the inserted disks *t*, and *t'* having spherically-formed exterior surfaces which bear against the back of the beam *A* of the car-frame and the strap *d'*, respectively. The object of the arrangement of the springs *c* and *c'* is that when the rods *a a* are tightened up by means of the hand-wheels *D*, &c., only the small spring *c'* will be compressed while the heavy one, *c*, will remain unmoved. When, however, the train is set in motion, the rods *a a* will be subjected to a strong pull and will compress the heavy springs *c c* to a certain extent, thus forming an elastic connection between the cars, which is very advantageous. The play which the frames *a³ a³* are allowed in the horizontal plane and their pointed or tapered edges will allow them to push by one another, that car which is most heavily loaded pushing its respective frames or loops underneath those of the other car, Fig. 7. In Fig. 5^a a similar device is shown, but with the hooks movable in the horizontal plane and the loops placed on edge or in the vertical plane. In this case the rods *M'* are not retained in position by pins *o* but by notches *m m*, which grip over the side of the guide-straps on the buffers, and are retained in position by means of suitable springs *pp*, inserted between the rod and the opposite side of the said guide-straps.

I claim as my invention—

1. In a car-coupling the combination of hooks pivotally attached to the car ends, frames elastically attached to the said car ends and arranged underneath said hooks, said frames being capable of receiving the hook above them and also the hook of the next car, means for letting down the said hooks into the said frames when overlapping each other and means for tightening up the same substantially as described.

2. In a car-coupling the combination of the pivotally-attached hooks *g g*, frames *a' a'* having rods or bars *a* elastically attached to the car-frame, eccentrics *B* having supporting-rod *h* and hooks *i* at the opposite side to the throw of said eccentrics a shoulder to the said hook *g* over which the hooks *i* grip, weighted levers *H* to the said eccentric-rod *h* and means for tightening up the said frames onto the hooks substantially as described.

3. In a car-coupling the combination of the pivoted hooks *g g*, frames *a' a'* on bars *a a*, a sleeve *b* having coarse exterior screw-thread and arranged on the said bars *a* behind the car-frame, an exterior sleeve *d²* to engage the thread of sleeve *b*, a worm-wheel *d'* to said sleeve, a worm *f* on worm-shaft *D'* mounted in the car-frame and means to turn said worm-shaft, a nut on the end of the said bar *a* and an inserted spring *c* arranged between the end of the sleeve *b* and the said nut substantially as described and means for raising and lowering the hooks *g g* as specified.

4. In a car-coupling the combination of
hooks $g' g'$ pivotally attached to the car ends,
frames $a^3 a^2$ having tapered ends elastically
attached to the said cars and means for tight-
ening up said frames, a bar M to operate said
hooks and means for arresting the said bar in
position substantially as described and shown.

In testimony whereof I have signed this
specification in the presence of two subscrib-
ing witnesses.

CARL MORADELLI.
